United States Patent Office

Des. 191,493
Patented Oct. 10, 1961

191,493

SODA FOUNTAIN OR SIMILAR ARTICLE

Herbert L. Smith, Van Nuys, Calif., assignor to S. Jerome Tamkin, doing business as Phillips Manufacturing Co., Los Angeles, Calif.

Filed Apr. 10, 1961, Ser. No. 64,693

Term of patent 14 years

(Cl. D2—3)

FIG. 1 is a perspective view of a soda fountain or similar article showing my new design;

FIG. 2 is a plan view;

FIG. 3 is a front elevational view;

FIG. 4 is a side elevational view showing the right side thereof; and

FIG. 5 is a bottom view.

I claim:

The ornamental design for a soda fountain or similar article, substantially as shown.
